UNITED STATES PATENT OFFICE.

FRANK A. BRENNER, OF SOUTH BEND, INDIANA, ASSIGNOR TO THE STUDEBAKER CORPORATION, OF SOUTH BEND, INDIANA, A CORPORATION OF NEW JERSEY.

MACHINE FOR PLACING PISTON RINGS ON PISTONS.

Application filed August 28, 1923. Serial No. 659,821.

To all whom it may concern:

Be it known that I, FRANK A. BRENNER, a citizen of the United States of America, and resident of South Bend, in the county of St. Joseph and State of Indiana, have invented certain new and useful Improvements in Machines for Placing Piston Rings on Pistons, of which the following is a specification.

10 This invention relates to machines for use in the assembling of piston-rings on pistons, and the principal object is to provide a machine that will allow piston-rings to be properly placed on pistons in a quick, accurate, and easy manner and which will be mechanical in operation and easy to operate.

15 A further object is to provide a machine having a piston supporting member and a sleeve adapted to carry a quantity of piston-rings, and means to force the piston-rings off the end of the sleeve into the grooves provided in the piston to receive the piston-rings.

20 A further object is to provide means for bringing the grooves in the piston into registry with the end of the sleeve on which the piston-rings are carried so that when the piston-rings are pushed off the sleeve they will be received in the grooves.

25 30 A still further object is to provide a piston-ring supporting member which can be detached from the machine for replacing piston-rings thereon and which is secured to the frame of the machine against vertical movement when in assembled position.

35 Still another object is to provide a piston-ring supporting sleeve which has an enlarged end adapted to fit over a piston on which piston-rings are to be placed and 40 which will expand the piston-rings prior to their being placed in the grooves in the piston.

45 Further objects, and objects relating to details of manufacture and construction will definitely appear from the detailed description to follow.

50 Heretofore the devices used for placing piston-rings on pistons have been more or less of a make-shift nature, making the operation slow and tedious, causing many of the rings to be broken because of too much of the human element entering into the operation, and for other causes. Having this in mind I have invented a device for placing piston-rings on pistons in a quick and

5 accurate manner, the device being essentially mechanical in operation and easy to operate.

60 In the accompanying drawings which show an embodiment of my present invention:

65 Figure 1 is a fragmentary sectional side view taken through the center of a machine embodying my present invention, and showing a piston in connection therewith in the operation of having piston-rings applied thereto.

70 Figure 2 is a development of the surface of the cam member which supports the piston, a piston being shown at one side to illustrate the relation between the cam track and the piston-ring grooves.

75 Figure 3 is a horizontal section of the device taken on the line 3—3 of Figure 1.

80 Referring to the numbered parts of the drawings, 4 is a frame, the upper portion of which is provided with a vertical opening in which a sleeve 5 is adapted to slide. A rack-gear 6 is secured to one side of the sleeve 5 by the screws 7 and a spur gear 8 keyed to the spindle 9 journaled in the frame 1, as clearly shown in Figure 3, meshes with the rack gear 6 to move the gear 6 and sleeve 5 connected thereto in a vertical direction, 85 for a purpose which will presently be described. An operating handle 10 secured by the pin 11 to the end of the spindle 9 is provided with arms or levers 12 which can readily be gripped by the operator to turn the spur-gear 8 and thereby raise or lower the sleeve 5.

90 A second sleeve 13 having its upper end extending upwardly within the sleeve 5 is held against vertical movement by the removable pin 14 which passes through the frame 4 and sleeve 13 to retain the sleeve 13 in its fixed position. The sleeve 5 is provided with a slot 15 to allow the sleeve 5 to move up and down within the frame 4 and without interference with the sleeve 13. The

95 body portion of the sleeve 13 is of slightly smaller outside diameter than the inside diameter of the free piston rings 16 adapted to be loaded thereon, and its lower end is slightly bulged and recessed to allow a piston 17, which is to receive the rings 16 to slidably enter the same, the sleeve 13 immediately surrounding the piston having relatively thin walls. A cable 18 secured by the eye 19 to the sleeve 5 extends

100 over the sheave 20 journaled in the 110

bracket 21 which is secured by the screws 22 to the upper portion of the frame 4, and passes down over the sheave 23 journaled in the bracket 24 secured by the screws 25 to 5 the side of the frame 4. A weight 26 is secured to the free end of the cable 18 by means of the eye 27, and counterbalances the weight of the sleeve 5 and rack 6.

Directly below and concentric with the 10 vertical opening in the upper part of the frame 4 in which the sleeve 5 is slidably mounted is another vertical opening 28 in the frame 4 adapted to receive a piston supporting member 29 which is rotatable and 15 slidable therein. A cam track 30 is formed in the surface of the member 29, and a roller 31 rotatably mounted on the pin 32 threaded into the frame 4 surrounding the opening 28 seats in the track 30. The upper 20 end of the piston supporting member 29 is formed to receive the lower end of the piston 17 thereon, and levers or handles 33 secured in the member 29 provide means for 25 rotating the same. As before stated, the sleeve is held in fixed position in the frame 4 by means of the removable pin 14, and the cam track 30 is so formed in the piston supporting member 29 that upon rotation of the member 29 by means of the handles 33, 30 the same can be lowered sufficiently to allow the piston 17 to be placed thereon beneath the sleeve 13. The cam track 30 is formed with four short horizontal portions 34, 35, 36 and 37, corresponding to the four grooves 35 of the piston 17, and rotation of the member 29 will bring these horizontal portions of the track 30 successively in contact with the roller 31, in each of which positions the extreme lower edge of the sleeve 13 is flush 40 with the upper edge of the corresponding ring groove in the piston 17. Shallow recesses, or depressions 38 are provided in the member 29 in a position corresponding to the horizontal portions 34, 35, 36 and 37 of the track 30, and a detent 39, normally pressed inwardly towards the center of the opening 28 by the spring 40 backed by the plug 41 threaded into the frame 4 surrounding the opening 28, is adapted to enter the recess 38 corresponding to the horizontal portion of the cam track 30 which may be in contact with the roller 31. The purpose of the recess 38 and detent 39 is to prevent the piston supporting member 29 from being 50 inadvertently moved when one of the horizontal portions of the track 30 is in contact with the roller 31. The relation of the cam track to the piston-ring grooves of the piston 17 is clearly shown in Figure 2.

The operation of the machine is as follows: For convenience it will be assumed that a sleeve 13, loaded with piston rings 16, is properly supported in position as shown 60 in Figure 1 and the member 29 has been rotated to a point where the end 42 of the

cam track 30 (clearly shown by the developed surface of the member 29 in Figure 2) and the roller 31 are in contact. As the end 42 of the cam track 30 is the highest point of the track 30, it will thus be seen 70 that when the member 29 has been rotated so that the end 42 in the track 30 contacts with the roller 31, the member 29 has been lowered to a position which allows the piston 17 to be placed on the member 29. The 75 member 29 is then rotated so that the flat portion 34 of the cam track 30 comes in contact with the roller 31, the detent 39 dropping into a recess 38 corresponding to the flat portion 34, thus holding the member 80 29 in such position that it carries the piston 17 up within the recess formed in the lower part of the sleeve 13, to a point where the lower end of the sleeve 13 is flush with the upper edge of the lowest piston-ring groove 85 in the piston 17. The levers 12, controlling indirectly the position of the sleeve 5, are then operated to lower the sleeve 5 (which causes the piston-rings 16 to slide down the sleeve 13) an amount necessary to force one 90 ring off of the lower end of the sleeve 13, and inasmuch as the lower edge of the sleeve 13 and upper edge of the lower ring groove are flush, the piston-ring 16 thus forced off of the lower end of the sleeve 13 contracts 95 into the lower ring groove. The member 29 is then rotated to bring the flat portion 35 of the track 30 in contact with the roller 31, the detent 39 acting as before. This 100 rotation of the member 29 causes the piston 17 to be lowered an amount necessary to bring the lower edge of the sleeve 13 and the upper edge of the next-to-the-bottom ring groove flush with each other, and the levers 12 are again operated to force off 105 another ring 16 from the sleeve 13 which drops into its groove. The member is then rotated until the portions 36 and 37 of the track 30 successively come in contact with the roller 31, at each of which points a ring 110 16 is forced off of the sleeve 13 into the corresponding groove in the piston 17. As the operations described have filled each groove of the piston 17 with a ring 16, the member 29 is rotated back until the end 42 again 115 comes in contact with the roller 31, at which point the loaded piston 17 is removed and one without rings replaces it to go through the same operations.

When all the piston-rings 16 on the sleeve 120 13 have been used, the member 29 is dropped to its lowest position, the sleeve 5 is raised to its highest position, the pin 14 is removed, and then the sleeve 13 is removed and another one loaded with rings 16 replaces it, 125 whereupon the operation of placing the rings on the piston is repeated.

It will be noticeable that this device is capable of very fast operation, and that every ring is quickly and accurately 130

dropped into its respective groove, with no tendency for the ring to become "cocked" and therefore broken. It is also obvious that a variety of members 29 may be provided with different cam tracks 30 to accommodate pistons with different spacings between the ring grooves.

Inasmuch as it is desirable in this machine to have the lower end of the sleeve 13 extend down over the piston 17, higher stresses in the rings being placed on the pistons are liable to occur than in the old hand method where no sleeve of any sort is used. In order to obviate any difficulty from this source I prefer, in large production, to have several sleeves 13 constantly loaded with rings and placed in an oven to bring their temperature up to a point where the stresses developed from spreading the rings over the lower bulged portion of the sleeve 13 is materially reduced, and if thought advisable an electric heating element such as 43 may be inserted within the sleeve 13 during the operation of loading rings on pistons, in order to keep the temperature up to a sufficient degree.

It is evident that formal changes may be made in the specific embodiment of the invention described without departing from the spirit or substance of the broad invention, the scope of which is commensurate with the appended claims.

Having thus described my invention, what I claim is:

35 1. A device for placing piston rings on pistons, comprising a piston-ring receiving member; a piston supporting member; means for causing piston-rings to be forced off of one end of said piston-ring receiving member; and means for bringing said end of said piston-ring receiving member and the edge of a groove in a piston supported on said piston supporting member to a position in which they are flush with each other.

45 2. A device for placing piston-rings on pistons, comprising a stationary piston-ring receiving member, a piston supporting member adjacent one end of said piston-ring receiving member adapted to be moved to and from the same, and means for forcing piston-rings off of the end of said piston-ring receiving member adjacent said piston supporting member.

55 3. A device for placing piston-rings on pistons, comprising a sleeve and means for longitudinally moving said sleeve, a second sleeve immovably positioned within the first mentioned sleeve, a piston support adjacent the end of said second sleeve, and means for controlling the position of said piston support.

60 4. A device for placing piston-rings on pistons, comprising a frame, a sleeve longitudinally slidabie in said frame, means for moving said sleeve longitudinally, a piston-

ring receiving member removably attached to said frame within said sleeve, a supporting member axially coincident with said sleeve positioned adjacent one end of said ring receiving member, and means for controlling the position of said supporting member.

65 5. A device for placing piston rings on pistons, comprising a piston-ring receiving member, one end of which is provided with a recess adapted to receive a piston, a supporting member for said piston, means for raising or lowering said piston supporting member whereby the upper edge of the piston-ring grooves in said piston may be brought substantially flush with the adjacent end of said piston-ring receiving member; and means for forcing piston-rings off of said adjacent end of said piston-ring receiving member into said piston-ring grooves.

70 6. A device for placing piston-rings on pistons, comprising a frame; a piston-ring receiving member; means for forcing piston-rings off of one end of said piston-ring receiving member; a piston supporting member adjacent said end, having a cam track in the surface thereof to provide longitudinal and rotatable movement of said member; and a roller engaging said cam track supported by said frame, said cam track being formed to cause a change in longitudinal position of said piston receiving member when the same is rotated.

75 7. A device for placing piston-rings on pistons, comprising a frame; a stationary piston-ring receiving member removably supported in said frame; means for forcing piston-rings off of said piston-ring receiving member; a piston supporting member adjacent one end of said piston-ring receiving member having a cam track in the surface thereof; a roller engaging said cam track mounted on said frame, said cam track being so formed that rotation of said piston supporting member will bring the upper edge of a piston-ring groove in a piston mounted thereon flush with the adjacent end of said piston-ring receiving member; and means for holding said piston supporting member in such position.

80 8. A device for placing piston-rings on pistons, comprising a piston-ring receiving member; a piston supporting member; means for forcing piston-rings off of said piston-ring receiving member; means for causing one end of said piston-ring receiving member to become substantially flush with one edge of a groove in a piston supported on said piston supporting member; and means for maintaining the temperature of piston-rings on said piston-ring receiving member above their normal temperature.

85 9. A device for placing piston-rings on pistons, comprising a frame; a sleeve longi-

- tudinally slidable in said frame, a rack-gear secured to said sleeve and extending in the direction of the length of the sleeve; a shaft journaled in said frame; a spur gear secured 5 on said shaft and adapted to mesh with said rack gear; means for rotating said shaft; a piston-ring receiving member having its lower end enlarged to receive a piston extending within said sleeve, and being removably secured in said frame; a piston supporting member positioned adjacent one end of said piston-ring receiving member and axially coincident therewith having a cam track in the surface thereof to provide 10 rotatable and longitudinal movement, and a roller mounted in said frame adapted to seat in said track; said track being so formed that rotation of said piston supporting member will bring the upper edges of 15 the ring grooves in a piston supported thereon successively to a flush position with the lower edge of said piston-ring receiving member.
10. A device for placing piston rings on pistons, comprising a piston ring receiving member; a piston supporting member; means for forcing said piston rings off of one end of said piston ring receiving member; and means for raising and lowering said piston supporting member to bring the successive grooves in said piston into position to receive said piston rings. 20

Signed by me at South Bend, Indiana,
this 27th day of August, 1923.
